W. J. MALONEY,
ATTACHMENT FOR WARPING MACHINES
APPLICATION FILED JUNE 8, 1920.

1,378.257.

Patented May 17, 1921.

Fig. 1.

UNITED STATES PATENT OFFICE.

WILLIAM J. MALONEY, OF ANSONIA, CONNECTICUT.

ATTACHMENT FOR WARPING-MACHINES.

1,378,257.

Specification of Letters Patent. Patented May 17, 1921.

Application filed June 8, 1920. Serial No. 387,284.

To all whom it may concern:

Be it known that I, WILLIAM J. MALONEY, a citizen of the United States, residing at Ansonia, county of New Haven, State of Connecticut, have invented an Improvement 5 in Attachments for Warping-Machines, of which the following is a specification.

The object of the present invention is to provide an attachment for warping machines which will properly guide and tension 10 the threads as they pass from the creel to the spool and cause them to be wound upon the spool in an improved manner.

With the above and other objects in view, 15 the invention comprises the construction, arrangement and combination of parts as now to be fully described and hereinafter specifically claimed.

In the accompanying drawing forming a 20 part of this specification,

Figure 1 is a top plan view of so much of a warping machine as is necessary to disclose the invention, the upper plate of the attachment being broken away to better 25 show the adjustable guide blocks; and

Fig. 2 is a sectional view on line 2—2 in Fig. 1.

The frame of the machine consists of a trevis 10 to the opposite ends of which are 30 attached parallel side arms 11, and an angle piece 12 which is parallel with the trevis and extends between and is supported by the parallel side arms. The angle piece supports a reed 13 through which the threads pass 35 and which is adjustable transversely of the side arms, the adjustable connection being made in any ordinary or preferred manner. As shown, bolts 14 pass through the reed and through elongated slots in the angle 40 piece and are provided with wing nuts 15. It will be noted that in the present structure the reed reciprocates in unison with the trevis, so that the angle of the threads between the reed and the guide blocks never 45 changes as the trevis moves back and forth in front of the spool, thus eliminating the bunching and overlying of the threads which occurs in ordinary warping machines wherein the trevis only moves.

50 16 denotes a creel, which may be located in any desired position back of the reed, 17 threads which are to be drawn from the creel, and 18 a spool upon which the threads are to be wound. The spool, as shown, is 55 positioned in front of and arranged parallel with the trevis.

The attachment of the invention comprises upper and lower plates, denoted by 19 and 20, respectively, upright rods 21 which extend between the plates to space them from each other, a sliding bar 22 which is provided with openings through which the upright rods freely pass, adjustable guide blocks 23 which are carried by the sliding bar, springs 24 one end of each of which is secured to the upper plate as indicated at 25 and the other end of each of which is secured to the sliding bar, as indicated at 26, to cause said bar to be yieldingly supported from the upper plate, and means for 60 adjustably supporting the lower plate from the trevis of the warping machine. The guide blocks are adjustable from and toward each other on the sliding bar, the adjustable connection, as shown, being made by 65 means of bolts 27 which pass through the guide blocks and through elongated slots 28 in the sliding bar and are provided with nuts 29 by which the guide blocks can be rigidly secured to the sliding bar. The lower 70 plate is carried by a supporting block 30, bolts 31 passing through said plate and block to secure them to each other, which in turn is adjustably supported by a U-shaped member 32 secured to the trevis as indicated 75 at 33. The front edge of the supporting block is adapted to rest against the base of the U-shaped member, as clearly shown, and the arms of the U-shaped member extend 80 rearwardly from the trevis and are located 85 on either side of and at spaced distances from the supporting block. A micrometer adjusting screw 34, carried by the arms of the U-shaped member and engaging a threaded transverse opening, in the supporting 90 block, provides means whereby the supporting block may be adjusted longitudinally of the trevis, as will be obvious. As shown, the micrometer adjusting screw is provided with a washer 35, a cross pin 36 100 and a holding spring 37 by which its position in the arms of the U-shaped member is insured.

The trevis, and consequently the frame, and the reed are adapted to reciprocate as 105 the threads are being wound upon the spool. Any convenient means may be provided to cause this reciprocation. In Fig. 2 I have suggested a slide 38 which is secured to the trevis for this purpose. The slide is arranged between guides 39 and is provided with a rack which is adapted to be given

the proper reciprocatory actuation by means of a pinion in a well known manner. The spool is preferably frictionally driven, as is also suggested in Fig. 2. The periphery 5 40 of a drum 41 journaled in ways 42 and rotated in any convenient manner is held in engagement with the thread on the spool to cause the spool to be rotated and additional thread to be wound thereon as will 10 be understood. A weight 43 suspended from a cord 44 which passes over a pulley 45 and is attached to the drum as denoted at 46, furnishes suitable means for insuring contact between the periphery of the drum and 15 the thread on the spool. The friction drive described provides for uniform removal of the threads from the creel.

As shown more clearly in Fig. 1, I preferably provide a guide rod 47 to better insure 20 the proper position of the threads as they pass between the guide blocks and prevent the threads from flying back and becoming entangled should a break occur in the threads between the sliding bar and the 25 spool. The threads pass beneath the guide rod, as clearly disclosed, and the opposite ends of the rod are loosely and slidably carried by the guide blocks.

The creel, as hereinbefore mentioned, may 30 be located in any desired position behind the reed. The threads to be wound upon the spool are first led from the creel and passed through their proper holes in the reed, are then made to pass between the 35 guide blocks and beneath the guide rod in flat fashion, are then led to the spool, and are then wound upon the spool to a sufficient extent to allow the friction drive to become operative. When now the drum is rotated 40 and the frame is given the proper reciprocation, the threads, it will be obvious, will be caused to wind up on the spool in flat fashion. That is, regardless of the number of threads being fed to the spool, the threads 45 as they go on the spool will be side by side and will not cross each other as has heretofore been so in the case of attachments of the present character.

As shown more clearly in Fig. 2, I arrange 50 the spool in proper position with respect to the sliding bar so that the threads will at all times be free from slack and under the proper tension for winding. That is, the springs which are secured to the upper 55 plate and yieldingly support the sliding bar are at all times under tension. As suggested in full and dotted lines in Fig. 2, as the diameter of the spool becomes increased in the winding operation, the sliding bar is 60 adapted to be drawn upwardly by the springs.

What I claim is:

1. In a warping machine, the combination 65 with a reciprocable trevis, thread tensioning and guiding means on the trevis, and a

reed carried by said trevis whereby the angle of the threads between the guide and the reed is uniform during operation.

2. In a warping machine, the combination 70 with a reciprocable trevis, thread tensioning and guiding means on the trevis, means for adjusting the same longitudinally with respect to movement of the trevis, and a reed carried by said trevis.

3. In a warping machine, the combination 75 with a reciprocable trevis, thread guiding means carried thereby, and a reed carried by the trevis.

4. A warping machine attachment comprising a trevis and a reed carried thereby, 80 an upright frame supported on the trevis, a thread carrying bar slidably mounted in said frame, means for yieldably supporting said bar in operative position, and guides on said bar.

5. A warping machine attachment comprising a trevis and a reed carried thereby, 85 an upright frame supported on the trevis, a thread carrying bar freely movable on the side bars of said frame, springs depending 90 from the top of the frame and yieldably supporting said bar, and adjustable guides on said bar.

6. A warping machine attachment comprising a trevis and reed carried thereby, 95 an upright frame, a thread carrying bar yieldably mounted in said frame, guide blocks carried by said bar, a guide rod carried by said blocks, and an adjustable supporting block carried by said trevis upon 100 which the frame is mounted whereby the same may be adjusted longitudinally with respect to the movement of the trevis.

7. A warping machine attachment comprising a trevis and a reed carried thereby, 105 an upright frame, a thread carrying bar yieldably mounted in said frame, guides carried by said bar, a U-shaped bracket carried by the trevis, a rotatable screw extending through the arms of said bracket, a 110 block co-operatively mounted on the same, and means for securing the frame to said block.

8. A warping machine attachment comprising 115 guide blocks which are adapted to be supported from the trevis of the warping machine, and means associated with the trevis whereby said guide blocks may be adjusted longitudinally of said trevis, said means consisting of a U-shaped member 120 which is secured to the trevis, a supporting block which is located between the arms of the U-shaped member, and a micrometer screw which is located in said arms and engages a transverse threaded opening in said supporting block.

9. A warping machine attachment comprising 125 an upper and a lower plate, upright rods extending between the plates to space them from each other, a sliding bar freely

carried by said upright rods and yieldingly supported from said upper plate, guide blocks carried by said sliding bar, a supporting block by which said lower plate is carried, and means secured to the trevis of the warping machine for adjusting said supporting bar longitudinally of said trevis.

10. A warping machine attachment comprising an upper and a lower plate, upright rods extending between the plates to space them from each other, a sliding bar freely carried by said upright rods and yieldingly supported from said upper plate, guide blocks carried by said sliding bar, a supporting block by which said lower plate is carried, and means for adjusting said supporting block longitudinally of the trevis of the warping machine, said adjusting means consisting of a U-shaped member which is secured to the trevis and the arms of which extend to either side of the supporting block, and a screw which is carried by said arms and engages a transverse threaded opening in said supporting block.

25. 11. A warping machine attachment comprising a U-shaped member which is secured to the frame of the warping machine, a supporting block located between the arms of said U-shaped member, an adjusting screw carried by said arms and adapted to engage a transverse threaded opening in said supporting block, and a plurality of guide blocks carried by said supporting block.

30. 12. A warping machine attachment comprising a U-shaped member which is secured to the frame of the warping machine, a sup-

porting block located between and spaced from the arms of said U-shaped member, an adjusting screw carried by said arms and adapted to engage a threaded transverse 40 opening in said supporting block, and a plurality of yieldingly supported guide blocks carried by said supporting block.

13. A warping machine attachment comprising a U-shaped member which is secured to the trevis of the warping machine, a supporting block located between and spaced from the arms of the U-shaped member, an adjusting screw carried by said arms and adapted to engage a threaded transverse 45 opening in said supporting block, whereby said supporting block may be adjusted longitudinally of said trevis, and thread guiding and tensioning means carried by said supporting block, said guiding and tensioning means comprising a pair of spaced apart plates, upright rods extending between the plates, a sliding bar loosely carried by the upright rods and yieldingly supported from one of the plates, and guide 50 blocks carried by the sliding bar.

14. In a warping machine, a reciprocating frame, a trevis and a reed carried by the frame, means for adjusting the reed longitudinally with relation to the trevis, upright rods carried by the frame, a sliding bar freely movable on the rods, adjustable guide blocks on the bar, and means for yieldingly supporting the bar.

In testimony whereof I affix my signature. 70

WILLIAM J. MALONEY.
